GEORGE HORATIO PACKWOOD

PATENT OFFICE.

GEORGE HORATIO PACKWOOD, SR., OF TAMPA, FLORIDA.

TYPE-WRITER ATTACHMENT.

1:192,556

Specification of Letters Patent. Patented July 25, 1916.

Application filed December 30, 1914. Serial No. 879,643

To all whom it may concern:

Be it known that I, GEORGE H. PACKWOOD, Sr., a citizen of the United States, and a resident of Tampa, in the county of Hillsboro and State of Florida, have invented certain new and useful Improvements in Type-Writer Attachments, of which the following is a specification.

My invention relates to typewriting machines, and one of the main objects thereof is to provide means, located at the key-board, for releasing the carriage from its escapement to permit it to be automatically carried to any desired point by means of its spring; a further object is to provide an adjustable stop which is normally out of carriage stopping position, but which is moved into such position by the same means which releases the carriage from its escapement; a further object is to provide a substitute for the present rack-bar on Remington typewriters, which substitute is formed of channeled metal and serves a dual purpose hereinafter set forth; and a further object is to so construct the attachment as to be applied to present machines without any alteration therein.

My invention is fully described in the following specification, of which the accompanying drawings form a part, in which like reference characters are used to designate like parts in each of the views, and in which:

Figure 1 is a side elevation of a conventional typewriter provided with my attachment, and partly broken away; Fig. 2 is a fragmentary plan view thereof, with the carriage in intermediate position; and Fig. 3 is a detached, fragmentary, view of a detail.

In the drawings forming a part of this application I have shown a conventional typewriter having a base 4, keys 5 forming the keyboard, carriage 6, escapement 15 ratchets 7, escapement pinion 8, all of the usual form, and with the last of which is normally engaged a rack-bar 9, said carriage also carrying a fixed arm 10 movable therewith, the rack-bar 9 also moving with said carriage. The rack-bar 9 is carried by two arms 11 pivoted, at 12, to blocks 13 adapted to be secured to the carriage by screws 14, or equivalent, and it will be seen that said rack-bar may thus be raised vertically out of engagement with the escapement pinion 8 to permit free carriage move- 50 55

ved est patente que est bas. At adcoold
about last Saturday now has opened. He having several
notices of the same you should make your
application as soon as possible. I think you will get a
PATENT OFFICE.
I am told he is very busy, but I am sure you will get
your patent in time. I am sending you a copy of the
patent application, so you can see what I have done.
Yours truly,
JOHN W. COOD, SR., OF TAMPA, FLORIDA.

ment by means of its spring, not shown. In the preferred form of construction I form the teeth of the rack-bar on one member of a plate 15 bent into channeled form, U-shaped in cross section, as clearly shown in Fig. 1, and the other member 16 of which is confined between the side flanges of a roller 17 carried by a horizontal portion of a rod 18 having also a main vertical portion 19 and a supplemental horizontal portion 20. The rod 18 is in pivotal connection with a key-bar 21 pivoted at 22 and having a key 23 at the front end thereof, and it will be seen that, if the key 23 be depressed, the rod 18 is raised, carrying the roller 17 therewith, and releasing the rack-bar 9 from the pinion 8, the member 16 of the plate 15 being then carried by the roller 17 in the movement of the carriage to the left by means of its spring. I also provide two standards 24 upon the top of the machine frame, and in the top of which is pivoted a toothed bar 25 normally arranged at an angle to the horizontal portion 20 of the rod 18 and upon which it bears, and it will be seen that, if the key 23 be depressed, this bar 25 is moved on its pivots into horizontal position approximately, simultaneously with the clearance of the rack-bar 9 from the pinion 8.

Slidable along the bar 25 is a stop 26 having teeth adapted for engagement with the teeth of said bar to hold said stop at any desired point along the length of the bar, spring finger clips 27 serving to hold the same in adjusted position against downward movement, and, when the bar 25 is released as just described, the stop 26 enters the path of movement of the arm 10 which strikes said stop and prevents further carriage movement by means of its spring; when the key 23 is released, the rack-bar is again engaged with the pinion 8, the stop 26 drops out of the path of the arm 10, and normal operation of the machine may be resumed; when desired, the key 23 may be quickly and lightly tapped to raise the rack-bar out of pinion engagement for an instant, thus enabling the carriage to move a corresponding distance for each of said taps, this being in the event of a desire to have the carriage feed more rapidly than by the normal escapement operation in writing.

To install my device, all that is necessary is to drill the holes and tap the same for the screws holding the standards 24, arm 10,

blocks 13, and the lug carrying the key-
lever pivot 22, remove the conventional rack-
bar, and substitute my plate 15 therefor,
a suitable guiding hole being also provided,
5 if required, through the frame of the ma-
chine, for the vertical portion 19 of the rod
18, and, when the parts are in place as shown,
the device is ready for use.

It will be obvious that the stop 26 may
10 be adjusted in any desired position, as for
a column of figures, and it will also be ob-
vious that I may employ as many of the
stops as are required or desired to suit the
character of the work being done on the
15 typewriter; I may permit the carriage to
jump all the way from rest position to
stop position or by short jumps through deli-
cate taps on the key 23; I may then release
the carriage to jump to another stop, if two
20 or more are used, in one or a plurality of
jumps; and I may, after the last stop, op-
erate the machine in the usual manner.

While I have shown the device as applied
25 to a Remington typewriting machine, I do
not limit myself to this type, nor to any
specific type, neither do I limit myself to
the exact details shown and described, as
changes may be made thereover, either for
30 the type of machine illustrated or for other
types, my invention consisting, broadly, in
the provision of an attachment for the pur-
pose stated which may be quickly and easily
connected with a typewriter.

Having fully described my invention, what
35 I claim as new, and desire to secure by Let-
ters Patent, is:—

1. In a typewriting machine comprising a
frame, a carriage movable thereon, an es-
capement pinion, a rack bar engaging the
40 same and a plurality of keys, a tabulating
attachment consisting of a rigid arm pro-
jecting rearwardly from said carriage, a to-
othed bar pivotally secured to the frame
and normally held in an oblique position, a
45 stop adjustably locked to said toothed bar
on its toothed edge, a supplemental key, and
means operable by the depression of said
key for simultaneously lifting the rack bar
from the escapement pinion and swinging
50 the toothed bar on its pivots to a horizontal
position to carry the stop into the path of
said arm, said rack bar and stop being re-
turned to normal position in the upward
movement of the supplemental key.

55 2. In a typewriting machine, provided

with a frame, a carriage movable thereon,
an escapement pinion, and a rack bar en-
gaged therewith and a plurality of keys, a
tabulating attachment consisting of a rigid
arm detachably secured to said carriage and 60
projecting rearwardly therefrom, two stand-
ards detachably secured to the frame, a bar
having its lower edge toothed and pivotally
mounted on said standards, said toothed bar
normally held in an oblique position, a stop 65
adjustably locked to the toothed edge of said
bar, a supplemental key, a lever therefor in
detachable connection with said frame, and
means operable by said supplemental key
for simultaneously lifting said rack bar from 70
the pinion and swinging said toothed bar
on its pivots to a horizontal position to
carry the stop into the path of the rigid arm
on the carriage.

3. In a typewriting machine comprising a 75
frame, a carriage movable thereon, a plural-
ity of keys, an escapement pinion, and a
vertically movable rack bar engaging said
pinion, said rack bar being inverted U-shape,
the front wall having a toothed lower edge, 80
the lower edge of the rear wall being smooth,
the front wall normally engaged by the es-
capement pinion, a tabulating attachment
consisting of a rigid arm projecting rear-
wardly from the carriage, a bar pivotally 85
mounted on the said frame, a supplemental
key lever, a vertically disposed rod pivotally
connected at its lower end to said lever and
bent horizontally adjacent its upper end
forming an axle arm extending under the 90
pivotally mounted bar, a grooved roller
mounted on said axle arm, said roller sup-
porting the rear wall of the rack bar, and
an adjustable stop carried by the pivotally
mounted bar, whereby upward movement of 95
the vertically disposed rod by the key lever,
will disengage the front wall of the rack
bar from the escapement pinion and sim-
ultaneously swing the pivotally mounted bar
to a position to carry the stop thereon into 100
the path of the aforesaid rigid arm project-
ing from the carriage.

In testimony whereof I have signed my
name to this specification in the presence
of two subscribing witnesses.

GEORGE HORATIO PACKWOOD, SR.
